UNITED STATES PATENT OFFICE

112,589

DESIGN FOR A HANGER FOR TOILET ARTICLES OR THE LIKE

Stanley Lowen, New York, N. Y.

Application February 17, 1938, Serial No. 75,215

Term of patent 14 years

To all whom it may concern:

Be it known that I, Stanley Lowen, a citizen of the United States, residing at New York city, county of Bronx, and State of New York, have invented a new, original, and ornamental Design for a Hanger for Toilet Articles or the like, of which the following is a specification, reference being had to the accompanying drawing, forming part thereof.

Fig. 1 is a side view of the hanger, showing my new design.

Fig. 2 is a front view of the aforesaid hanger.

Fig. 3 is a perspective view thereof.

I claim:

The ornamental design for a hanger for toilet articles or the like, substantially as shown.

STANLEY LOWEN.
